CLAIM

The ornamental design for a mobile cabinet, as shown and described.

DESCRIPTION

FIG. 1 is a front perspective view of a mobile cabinet showing my new design;

FIG. 2 is a front elevational view thereof;

FIG. 3 is a rear elevational view thereof;

FIG. 4 is a top plan view thereof; and

FIG. 5 is a side elevational view thereof, the opposite side elevational view being a mirror image of that shown.

FIG. 1

FIG. 2

FIG. 3

FIG. 4

FIG. 5
